METHOD OF LAYING TILE FLOORS

Edwin B. Gates, Mertztown, Pa., assignor to The
Atlas Mineral Products Company, Mertztown,
Pa., a corporation of Pennsylvania

Application March 11, 1932, Serial No. 598,286

5 Claims. (Cl. 94—22)

This invention relates to an improved method of laying tile floors, particularly so called "sanitary floors" such as are required in food, dairy houses, etc.

The methods heretofore employed in the laying of tile floors include the manual pouring of the tile joints with bonding material, and involves the tedious process of pouring the various joints successively. It frequently happens that after this bonding material becomes cooled, shrinkage occurs, causing an unevenness in the floor as depressions occur in the joints. It then becomes necessary to go over the various joints and fill in where required, after which a smoothing off operation is necessary in order that a smooth even surface may be obtained. In addition to the tediousness of this process, it frequently occurs that in the filling in process voids or interstices occur, in which may accumulate foreign matter difficult, if not impossible, to remove.

The present method overcomes the several objections to the above mentioned method, as the joints in most instances may be all poured at one time and in a single operation, and all of the joints are properly filled so that a smooth, even and substantially monolithic surface is produced requiring no pointing up or filling in process.

The improved method for attaining this much desired result is more fully hereinafter described, reference being had to the attached drawing, wherein:

Fig. 1 is a plan view of a comparatively small section of a floor space and adjoining wall and showing an arrangement of tiles therein,

Fig. 2 is a similar view showing parts of the second and third steps of the improved process, Fig. 3 is a similar view showing a completion of the third step of the process and preparatory to pouring of the joints,

Fig. 4 is a similar view showing the floor after the pouring process,

Fig. 5 is an enlarged transverse sectional view taken through a portion of the floor and wall and illustrating the pouring process in operation, and

Fig. 6 is a similar view showing the appearance of the floor after the process is completed.

In carrying out the process, the bed or foundation upon which the floor is to be laid is smoothed and leveled off from wall to wall of the structure, and the bodies or tiles 7 are placed upon the bed in such relation that channels 8 are formed between the several tiles. The distance between the tiles will be governed by the width of channel required, but care must be taken that channels of the proper width be provided between all of the several tiles so that all of said channels will be intercommunicating. It is preferred that those tiles next adjacent to

the walls 9 of the building be spaced therefrom a substantial distance, this distance depending largely upon the total floor area of the building. The purpose of this space will be pointed out hereinafter.

With the tiles thus placed upon the bed, the various channels 8 are covered to provide inter-communicating conduits, this being most practically effected by placing over the tiles a sheet or strips of paper, rubber or other flexible or pliable material 10. The marginal portions of the sheet are shaped around the extreme outer edges of the marginal tiles so as to protect such edges, whereupon the edges of the paper are bent down into the floor bed across the space between the marginal tiles and the walls. The sheet material thus laid is weighted down, this being most practically effected by covering the sheet material with sand 11. The tiling thus laid and covered is now ready for the pouring process. This is accomplished by pouring into one of the channels a quantity of fluent bonding material sufficient to at least fill all of the intercommunicating channels. The pouring is performed preferably at intersecting channels at a point substantially remote from the edge tiles of the floor. In facilitating the pouring operation, a pouring cup or funnel 12 is applied to intersecting channels, by clearing away the sand and covering sheet immediately above the point of such intersection, whereupon the hot fluent bonding material is introduced to the pouring cup. This material immediately flows through the intersecting channels in all directions and fills the same evenly to the top surface of the tiles; the covering strips or sheet limiting the top level of the bonding material. It may be found desirable or necessary to vent one or more of the channels to insure a proper filling operation, and this may be accomplished by clearing away the sand and breaking the paper at a point such as represented at 13 in Fig. 2.

The pouring cup is of substantially frusto-conical shape having its small end in direct communication with the intersecting channels, and sand or mud may be packed around the upstanding cup as at 14 to maintain the same properly positioned. When the channels have been filled, the cup is filled nearly to its top with the fluent bonding material, and the pressure thus produced maintains the various channels properly filled to compensate for contraction in the bonding material incident to its cooling. This insures an even filling of all joints up to and flush with the top surface of the various tiles.

After cooling, the cup is removed and the sand and covering sheet taken away, after which the space 15 between the edge tiles and the wall 9 may be cleaned out and filled with a packing material represented at 16. This material consti-

tutes an expansion joint to compensate for creeping of the floor incident to varying temperatures.

In many instances, it will be found that all joints of a floor of given area may be poured at one operation, while, on the other hand, floors of larger area may require the use of several pouring cups, in order that a proper distribution of the fluent bonding material may be made in all of the channels. If the pouring operations are carried out simultaneously, the fluent materials from the several cups will meet and properly bond out each other due to the similarity of temperatures.

In the present instance there are shown tiles of square or rectangular formation, but it will be understood that the tiles may take other regular or irregular shapes as desired so long as the spaces or channels between the various tiles remain continuous or uninterrupted. In the present disclosure there is shown but a single vent 13 to relieve entrapped air in the channels, but it will be understood that other vents may be provided, either in the ends of the channels or the points of intersection thereof.

From the foregoing it is obvious that I have provided a method whereby a relatively large area of tile surface may be joined properly and effectively at a single pouring operation without the necessity of resorting to after treatment of any of the joints, either to fill the same in or to smooth off protuberances. While the method herein described sets forth a gravity pouring operation, it will be understood that other means may as effectively be used for introducing the fluent bonding material to one or more channel intersections of the tile layout. It will, moreover, be understood that the method may equally as well be carried out where several layers of tiles are employed, as the tiles of the upper layer may be properly spaced from those of the lower by the use of spacing elements to provide an uninterrupted channel. In the claims the term "body" is used to indicate the tile, and it will be understood that such term not only includes tiles of refractory material but also blocks or bricks of other characters.

Having thus described my invention, I claim:—

1. The method of laying tiling or the like, comprising arranging separate bodies upon a foundation with the bodies separated by intercommunicating channels, converting said channels into temporary intercommunicating conduits by superposing on the bodies a temporary cover sheet of flexible material so arranged as to extend across said channels, providing one or more vent openings in said cover sheet, causing a fluent bonding material to flow through said conduits and to fill said channels to a uniform level by pouring a sufficient quantity thereof through one or more openings in said cover sheet, and removing said cover sheet after said spaces have been filled.

2. The method of laying tiling or the like, comprising arranging separate bodies upon a foundation with the bodies spaced by intercommunicating channels, converting said channels into temporary intercommunicating conduits by superposing on the bodies a temporary cover sheet of pliable material so arranged as to extend across said channels, weighting said cover sheet so as to hold it in position, causing a fluent bonding material to flow through said conduits and to fill

said channels to a uniform level by pouring a sufficient quantity in through one or more openings in said cover sheet, and removing the cover sheet and the weighting means after said channels have been filled.

3. The method of laying tiling or the like, comprising arranging separate bodies upon a foundation with the bodies spaced by intercommunicating channels, converting said channels into temporary intercommunicating conduits by superposing on the bodies a temporary cover sheet of flexible material so arranged as to extend across said channels, weighting said cover sheet down with loose sand, venting one or more of said channels through said cover sheet and said sand, causing a fluent bonding material to flow through said conduits and to fill said channels to a uniform level by pouring a sufficient quantity thereof through one or more openings in said cover sheet and said sand, and removing said cover sheet and said sand after the channels have been filled.

4. The method of laying tiling or the like, comprising providing a foundation with enclosing walls, arranging separate bodies upon said foundations with the bodies spaced by intercommunicating channels, the marginal bodies being spaced from said walls, converting said channels into temporary intercommunicating conduits by superposing on the bodies a temporary sheet like cover so arranged as to extend across said channels and closing the outer ends of said conduits by folding the marginal edges of said cover downwardly over the outer edges of the marginal bodies and across the spaces interposed between the last mentioned bodies and the walls adjacent thereto, causing a fluent bonding material to flow through said conduits and to fill said channels to a uniform level by pouring a sufficient quantity thereof through one or more openings in said cover, removing said cover after said channels have been filled, and filling the space between the marginal bodies and said walls to a level even with the top surfaces of said bodies.

5. The method of laying tiling or the like, comprising providing a foundation with enclosing walls, arranging separate bodies upon said foundation with the bodies spaced by intercommunicating channels, the marginal bodies being spaced from said walls, converting said channels into temporary intercommunicating conduits by superposing on the bodies a temporary cover sheet of pliable material so arranged as to extend across said channels, closing the outer ends of said conduits by folding the margins of the cover sheet downwardly over the outer edges of the marginal bodies and across the space intervening between said last mentioned bodies and the walls adjacent thereto, weighting said cover sheet down with sand, venting one or more of said channels through said cover sheet and said sand, causing a fluent bonding material to flow through said conduits and to fill said channels to a uniform level by pouring a sufficient quantity thereof through one or more openings in said cover sheet and said sand, removing said cover sheet and said sand after the channels have been filled, and finally filling the spaces between the walls and the marginal bodies to a level even with the top surfaces of said bodies.

EDWIN B. GATES.
